PAPER-HANGING DEVICE

Herbert H. Johnson, Corning, Ark.

Application March 23, 1953, Serial No. 343,865

4 Claims. (Cl. 216—4)

This invention relates in general to paper hanging equipment, and more specifically to an improved device for applying paper to ceilings and the like.

At the present time, when one hangs paper on a ceiling of a room, it is necessary to first position planks in the room so that the paper hanger may conveniently reach the ceiling and directly apply paper thereto. Not only does such a process require the expenditure of time setting up the scaffolds, but also the hanging of paper becomes a tiresome operation due to the fact that the paper hanger must both continuously climb up and down off of the planks, but also reach overhead to apply the paper. It is, therefore, the primary object of this invention to provide an improved paper hanging device which may be conveniently utilized by a paper hanger while standing on the floor to apply paper to a ceiling of a room.

Another object of this invention is to provide an improved paper hanging device in the form of a supporting frame having a platform for receiving wallpaper which has been pasted and folded, and a guide means for aligning the paper with either a wall of the room or an edge of recently applied wall paper so that the wall paper being applied may be properly positioned prior to the pressing of the same onto the ceiling.

Another object of this invention is to provide an improved paper hanging device which is of relatively simple construction and which may be quickly and easily formed of readily obtainable materials so as to be economically feasible.

A further object of this invention is to provide an improved paper hanging device for facilitating the applying of wall paper to a ceiling by a paper hanger standing on the floor, said paper hanging device including a fixed guide and a movable guide, said movable guide being adjustable so as to accommodate various widths of papers, said guides controlling the path of wall paper passing off of the paper hanging device so that the same may be properly positioned.

A still further object of this invention is to provide an improved paper hanging device which includes suitable guide means for properly positioning paper on a ceiling or the like, said guide means including a gauge adapted to initially engage an edge of a previously applied course of wallpaper so as to insure a proper overlap of the course being applied.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary side elevational view of the paper hanging device, which is the subject of this invention, and which shows the same in position during a paper hanging operation;

Figure 2 is a fragmentary front elevational view of the paper hanging device of Figure 1 and shows the relationship of paper with respect to the paper hanging device during a stage of its installations;

Figure 3 is a top plan view of the paper hanging device as viewed from the ceiling of a room and shows the same in the process of applying a course of wallpaper in overlapping relation to a previously applied course of wallpaper;

Figure 4 is a bottom plan view similar to Figure 3 and shows the relationship of the paper hanging device with respect to the two courses of paper;

2

Figure 5 is a bottom plan view of the paper hanging device and shows the same in position prior to the application of a course of wallpaper in overlap relation to a previously applied course of wallpaper;

5 Figure 6 is an enlarged top plan view of the paper hanging device and shows the position of wallpaper with respect to the same, the wallpaper being shown in broken lines;

Figure 7 is an enlarged longitudinal vertical sectional view taken substantially upon the plane indicated by the section line 7—7 of Figure 3 and shows a specific construction of the paper hanging device and the relationship of wallpaper thereto;

10 Figure 8 is an enlarged perspective view of the gauge for determining the overlap of adjacent courses of wallpaper, the gauge being shown in a position inverted with respect to its normal position during use;

15 Figure 9 is a fragmentary side elevational view of the upper portion of a handle for retaining the paper hanging device in an elevated position; and

20 Figure 10 is an enlarged fragmentary front elevational view of the upper end of the handle.

Referring now to Figures 6 and 7 in particular, it may be seen that there is illustrated a paper hanging device, 25 which is the subject of this invention.

The paper hanging device 10 includes a pair of identical side frames 12 which are of a generally inverted U-shape. Each of the side frames 12 includes a forward depending leg 14 and a rear depending leg 16 which are connected together by a longitudinally extending web 18, the web being generally V-shaped so that the lower ends of the legs 14 and 16 lie in a common plane while being of a different height. It will be understood that the forward leg 14 is shorter than the rear leg 16.

30 35 Each side frame is braced by an L-shaped brace 20. Each L-shaped brace 20 has a free end of a horizontal leg portion in overlapping relation with the lower end of the rear leg 16 with which it is associated, the leg 16 and the corresponding leg of the brace 20 having portions removed so as to permit the L-shape brace 20 to lie in a common plane with its associated side frame 12. The leg 16 is connected to the L-shaped brace 20 by suitable fasteners 22.

40 45 The other leg of the L-shaped brace 20 has its upper end in overlapping relation to the central portion of the web 18. The overlapping portions of the web and L-shaped brace 20 are of reduced thickness to facilitate flushing mounting of the brace. The brace 20 is connected to the web 18 by suitable fasteners 24.

50 55 While the brace 20 has been illustrated and described as being separate from and secured to the associated side frame 12, it will be understood, that if it is so desired, the same may be made integral with its associated side frame 12.

55 60 Extending transversely between the L-shaped braces 20 and secured thereto at their lower forward corners by suitable fasteners 26 is a support bar 28. The support bar 28 is generally rectangular in cross-section and has a reduced portion 30 disposed as mid-point part of a section of a handle which is best illustrated in Figures 9 and 10, the handle being referred to in general by the reference numeral 32.

The handle 32 includes an elongated rod portion 34 whose upper end is enlarged and bifurcated as at 36. The bifurcated upper end results in the formation of a transverse notch 38. The notch 38 is of a width substantially equal to the width of the reduced portion 30 of the support bar 28 so as to facilitate engagement of a support bar with the handle 32 and the results in supporting of the paper hanging device 10 having an elevated position. In order to provide an increased seating area for the support bar 28, there is secured to opposite sides of the rod portion 34 adjacent its bifurcated upper end 36 a pair of inverted wedge shaped members 40. The wedge shaped members 40 have their upper ends terminating in alignment with the bottom of the recess 38 and engage the under side of the support bar 28 when the handle is in position. The wedge shaped members 40 are secured to the rod portion 34 by suitable fasteners 42.

65 70 75 80 Carried by the forward portion of the supporting frame which includes the side rails 12 is a transversely extend-

ing platform 44. The platform 44 has depending side flanges 46 which are secured to the inner surfaces of the forward portions of the side walls 12 by suitable fasteners 48. It will be noted that the platform 44 has the upper surface thereof in alignment with the upper edges of the webs 18 of the side rails 12 at their forward end portions. In order that folded and pasted wallpaper, which is referred to by the reference numeral 50, may be retained on the platform 44 and at the same time free to move longitudinally during a paper hanging operation, there are provided paper retaining means which are referred to in general by the reference numeral 52. The paper retaining means includes a transversely extending, inverted V-shaped lower section 54 which is secured to the upper surface of the platform 44 adjacent its forward ends by suitable fasteners 56. Hingedly connected to an upper portion of the section 54 is a second section 58. The second section 58 is generally rectangular in outline and has intermediate portions thereof twisted about the upper portion of the lower section 54 to form a hinge connection therebetween. The upper section 58 also includes a pair of centrally located legs 60 which are integral and connected together by a bend at their forward ends. The legs 60 are intended to form an operator for the upper section 58. It will be noted that the upper section 58 overlies and rests upon the wallpaper 50 to retain the same on the platform 44.

In addition to the platform 44 which also functions to connect together the forward ends of the side frames 12, and the support on 28 which connects together the L-shaped brace 20, the side rails 12 are connected together by transversely extending rods 62 and 64 which are longitudinally spaced and which pass through the rear portion of the webs 18. Disposed intermediate the rods 62 and 64 is a transversely extending bar 66 which has flanged ends 68 secured to the web 18. As is best illustrated in Figure 7, the upper extremities of the rods 62 and 64 and the bars 66 lie in a common plane.

Overlying the rods 62 and 64 and the bar 66 is the forward end of a Z-shaped aligning stick which is referred to in general by the reference numeral 68. The aligning stick 68 is generally rectangular in cross-section and includes a horizontal forward portion 70 and a horizontal rear portion 72, the portions 70 and 72 being in spaced relation and connected together by an intermediate portion 74 which is disposed at an angle to the portions 70 and 72.

The forward portion 70, as stated above, overlies and rests upon the rods 62 and 64 and the bar 66. The forward portion 70 is provided with a centrally located fastener 76 which may be selectively positioned in one of a plurality of apertures 78 in the bar 66, the apertures 78 being transversely spaced. It is to be understood that the aligning stick 68 is intended to form a guide for one edge of the wallpaper 50 with the inner surface of the web 18 of the opposite side frame 12 forming a guide for the opposite edge of the wallpaper 50.

Secured to the underside of the forward portion 70 adjacent the forward end thereof is a plate 80. The plate 80 is disposed between the bar 66 of the rod 64 and projects inwardly toward the center of the paper hanging device 10.

A somewhat similar plate 82 is also secured to the underside of the forward portion 70 of the aligning stick 68. The plate 82 is disposed rearwardly of the plate 80 and is positioned between the rod 62 and the bar 66. It will be noted that the plate 82 also projects inwardly toward the center of the paper hanging device 10.

As is best illustrated in Figure 7, the plates 80 and 82 have their upper surfaces in alignment with the upper extremities of the rods 62 and 64 and the bar 66 to function as a support for that portion of the wallpaper 50 passing thereover.

In order that the wallpaper 50 may be retained in edge abutting relation with the forward portion 70 of the aligning stick 68, the plate 82 has passed therethrough an elongated fastener 84 which is provided at its lower end with a handle 86. Disposed at the opposite end of the fastener 84 in overlying relation to the plate 82 is a clamp 88. The clamp 88 is urged downwardly toward the plate 82 by a spring 90 carried by the fastener 84 and abutting the underside of the plate 82 and a washer 92 rigidly carried by the fastener 84 above the handle 86.

It will be noted that the clamp 88 is positioned within a cut-out 94 in the forward portion 70 of the aligning

stick 68. It is intended that the fastener 84 be turned 90° to position the clamp 88 entirely within the notch 94 when it is desired to either engage or disengage wallpaper 50 with the aligning stick 68. Inasmuch as the wallpaper 50 is guided by the forward portion 70 of the aligning stick 68 and the web of the opposite side wall 12, it may be seen that the wallpaper passing from the paper hanging device 10 must remain in alignment with the paper hanging device at all times.

Referring now to Figures 1 and 7 in particular it will be seen that during a paper hanging operation the free end of the wallpaper 50 is pasted to the ceiling 96 of a room after the paper hanging device has been properly positioned. As the paper hanging device 10 is progressively moved away from the free end of the wallpaper 50, the wallpaper is pulled off of the platform 44 in position for application to the ceiling 96. And through the use of a brush 98, the wallpaper 50 may be brushed onto the ceiling in the conventional manner. Inasmuch as the wallpaper is carefully guided by the paper hanging device 10 and retained in alignment therewith, the paper applied will be in proper alignment as long as the paper hanging device 10 is positioned so that the rear portion 72 of the aligning stick 68 remains in and above the width its associated edge of the wallpaper 50, as is best illustrated in various figures of the drawings.

While adjacent courses of wallpaper are oftentimes applied in edge abutting relation, the easiest and most widely utilized method of applying wallpaper is to overlap edges of adjacent courses of wallpaper. While the overlapping of adjacent courses requires only the trimming of one edge of the wallpaper 50, the proper overlap must be maintained in order to align the pattern of adjacent courses. In order to facilitate alignment of adjacent courses, a wallpaper being hung or applied with the wallpaper hanging device 10, there is provided a gauge 100 which is best illustrated in Figure 8. The gauge 100 includes an elongated plate 102 which has secured to the underside thereof a handle 104. Disposed adjacent to one edge of the plate 102 is a pair of longitudinally spaced apertures 106 for the reception of suitable fasteners to be explained in more detail hereinafter. Disposed adjacent the opposite edge of the plate 102 are transversely elongated slots 108. The slots 108 receive fasteners 110 which adjustably secure a plate 112 to the upper surface of the plate 102.

The plate 112 is of the same length as the plate 102, but is of a greater width. Disposed adjacent the longitudinal edges of the plate 112 are upwardly projecting flanges 114 of a relatively narrow width.

Referring now to Figures 6 and 7 in particular, it will be seen that the rear portion 72 of the aligning stick 68 has secured to the outer edge thereof intermediate ends of a hinge 116. The hinge 116 has a portion thereof in overlying relation to the plate 102 and the plate is secured thereto by a pair of fasteners 118.

During a paper hanging operation the gauge 100 is disposed in a vertical plane in depending relation with respect to the aligning stick 68. When it is desired to properly position the paper hanging device 10 for the proper overlap of a next adjacent course of wallpaper 50, the gauge 100 is swung inwardly and upwardly to a horizontal position, as is best illustrated in Figure 5. At this time, the innermost flange 114 of the sheet 112 is engaged with a free edge of a recently applied course of wallpaper 50. The paper hanging device 10 is then disposed in parallel relation with respect to the free edge of the wallpaper 50 and the gauge 100 permitted to return to its vertical position. While retaining paper hanging device 10 in this position, a free end of the wallpaper 50 carried thereby is pasted to the ceiling 96 in the conventional manner. Then, the paper hanging device 10 is moved longitudinally of the room with the edge of the course of wallpaper 50 being applied that is in overlying relation with the previously applied course of wallpaper remaining in constant engagement with the aligning stick 68. This aligns the course of wallpaper 50 being applied with the previously applied course of wallpaper and the overlap remains constant.

While it is intended that the handle 32 be of a length to permit the positioning of paper hanging device 10 by paper hangers standing on the floor of the room and that the brush 98 be provided with a relatively long handle for manipulation from the same position, if desired, the handle 32 could be dispensed with and a

short brush 98 utilized, however, in this case it would be necessary for the paper hanger to stand on planks in the normal manner. It is to be understood that in either case the paper hanging device 10 will insure proper alignment of wallpaper being applied therewith.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A paper hanging device comprising, a supporting frame, a paper receiving platform carried by said frame, guide means carried by said frame adjacent said platform for guiding paper moving off of said platform during a paper hanging operation to insure alignment of the course of paper being applied relative to previously applied courses, said guide means being transversely adjustable to accommodate various widths of paper, said guide means adapted to engage the side edges of paper for a substantial distance.

2. A paper hanging device comprising, a supporting frame, a paper receiving platform carried by said frame, guide means carried by said frame adjacent said platform for guiding paper moving off of said platform during a paper hanging operation to insure alignment of the course of paper being applied relative to previously applied courses, said guide means including a fixed side of said frame and a transversely adjustable aligning stick, said aligning stick being elongated and extending beyond the confines of said frame in a direction away from said platform.

3. A paper hanging device comprising, a supporting frame, a paper receiving platform carried by said frame, guide means carried by said frame adjacent said platform for guiding paper moving off of said platform dur-

ing a paper hanging operation to insure alignment of the course of paper being applied relative to previously applied courses, said guide means including a fixed side of said frame and a transversely adjustable aligning stick,

5 said aligning stick being elongated and extending beyond the confines of said frame in a direction away from said platform, paper support means carried by said aligning stick adjacent one edge thereof, means carried by said paper support means for retaining paper in engagement therewith and in edge abutting engagement with said one edge of said aligning stick.

4. A paper hanging device comprising, a supporting frame, a paper receiving platform carried by said frame, guide means carried by said frame adjacent said plat-

15 form for guiding paper moving off of said platform during a paper hanging operation to insure alignment of the course of paper being applied relative to previously applied courses, said guide means including a fixed side of said frame and a transversely adjustable aligning

20 stick, said aligning stick being elongated and extending beyond the confines of said frame in a direction away from said platform, paper support means carried by said aligning stick adjacent one edge thereof, means carried by said paper support means for retaining paper in en-

25 gagement therewith and in edge abutting engagement with said one edge of said aligning stick, the last mentioned means being spring urged into engagement with paper.
